INTERNAL COMBUSTION ENGINE

Harry L. Burkhardt, Santa Monica, Calif.

Application June 28, 1935, Serial No. 28,849

4 Claims. (Cl. 123—53)

This invention relates to mechanism for converting reciprocating motion to rotary motion, or vice versa, and is especially applicable to internal combustion engines for motor cars, airplanes, boats, and other purposes, but is also applicable to apparatus such as air compressors, pumps, and rock crushers.

The principal objects of the invention are to provide a mechanism in which the moving parts are in perfect dynamic balance and which will minimize the forces transmitted to the housing structure of the mechanism.

A further object is to provide a compact arrangement of the parts with the consequent saving of space, weight, and reduction in cost of manufacture.

The principal application of the invention is to internal combustion engines and I have chosen such engines for the purpose of disclosing herein illustrative embodiments of my invention.

In the accompanying drawings,

Fig. 1 is a longitudinal section through the cylinders of an internal combustion engine operating on the two-stroke cycle principle, the section being on the line 1—1 of Fig. 2;

Fig. 2 is a longitudinal section on the line 2—2 of Fig. 1;

Fig. 3 is an enlarged section through the motive fluid compressor, the section being on the line 3—3 of Fig. 2;

Fig. 4 is a detail elevation of the gears connecting the two crank-shafts of the engine;

Fig. 5 is an elevation at the end of one pair of cylinders showing the arrangement of the gas transfer connection between the cylinders;

Fig. 6 is a view similar to Fig. 1 but showing an engine operating on the four-stroke cycle principle;

Fig. 7 is a longitudinal section thereof on the line 7—7 of Fig. 6;

Fig. 8 is an end elevation of one of the pairs of cylinders and showing the arrangement of the valve actuating mechanism; and

Fig. 9 is a detail section on the line 9—9 of Fig. 7, showing the arrangement of the timing gears for operating the cam shafts.

It will be noted from the drawings that the parts of the mechanisms are units that are in common use and the physical characteristics of which are well understood. The illustrative embodiments are complete units, each comprising four cylinders, but it will be understood that these units may be duplicated to provide engines having eight or twelve cylinders or any other multiple of four cylinders, all having two crank-

shafts in common. Briefly, the illustrative embodiments of my invention each comprises two pairs of opposed cylinders and each cylinder being provided with its piston and connecting rod, the axes of the cylinders being arranged substantially in the same plane and each cylinder being directly opposite one of the cylinders of the other pair. Two crank-shafts, each having a single crank pin, are disposed between the pairs of cylinders with their axes normal to the plane of the cylinder axes. Two connecting rods connect each crank pin with the pistons of opposed cylinders, and the crank-shafts are geared together to rotate at equal angular velocities but in opposite directions. The crank pins are angularly positioned, relative to each other, to cause the reciprocating parts to move in the same direction at all times, and balancing weights of proper mass are disposed opposite each crank pin.

Referring to Figs. 1 to 5, it will be noted that there is a crank casing 10 having two pairs of bearings 11 for the crank-shafts 12 and 13. Secured to one side of the crank case 10 is a block comprising the cylinders 14 and 15 which may be suitably water-jacketed in accordance with well-known practice. The cylinder 14 has an annular inlet port 16 surrounding its inner wall and said wall is provided with a circumferential series of radial ports 17 whereby the port 16 communicates with the interior of the cylinder 14 in which the piston 18 reciprocates. A motive fluid supply pipe 19 connects with the port 16 and with the discharge orifice 20 of the compressor 21.

The cylinder 15 has an annular exhaust port 22, surrounding its inner wall, and a circumferential series of radial ports 23 extending therefrom to the interior of the cylinder in which the piston 24 reciprocates. An exhaust pipe or manifold 25 is connected to the port 22.

The piston 18 is connected with the crank 26, of the crank-shaft 12, by a connecting rod 27, and the piston 24 is connected with the crank 28, of the crank-shaft 13, by a connecting rod 29.

On the opposite side of the crank case 10, from the block containing the cylinders 14 and 15, there is a similar block containing the cylinders 30 and 31, the axis of the cylinder 30 being in alignment with the axis of the cylinder 14 and the axis of the cylinder 31 being in alignment with the axis of the cylinder 15. The cylinder 30 is provided with an annular inlet port 32, similar to the port 16, and the cylinder 31 is provided with an annular exhaust port 33, similar to the port 22, and in other respects the cylinders 30 and 31

31 are similar to the cylinders 14 and 15. The inlet port 32 has a branch of the motive fluid supply pipe 19 connected therewith and the exhaust port 33 has a branch of the exhaust pipe 5 or manifold 25 connected therewith.

There is a piston 34 in the cylinder 30 and a piston 35 in the cylinder 31 and the piston 34 is connected with the crank 26 by the connecting rod 36 and the piston 35 is connected with the 10 crank 28 by the connecting rod 37. The cylinders 14 and 15 are provided with a removable head block 38 having a port 39 therein for transferring the gases from the cylinder 14 to the cylinder 15, and it will be noted, from Fig. 5, that the transfer 15 passage 39 communicates with the cylinder 14 at one side and with the cylinder 15, at the opposite side, so that the gases will form and maintain the vortex or swirling motion in passing from one cylinder to the other. The usual spark plug is 20 indicated at 40. In a similar manner the cylinders 30 and 31 are provided with a head block 41 having a transfer port 42 therein and a spark plug 43.

The compressor 21 is shown in detail in Fig. 3 25 and comprises a housing 44 having the rotating impellers 45 and 46, constructed according to the well-known Roots blower principle. The impeller 45 is mounted directly on the crank-shaft 12 and the impeller 46 is mounted on the crank-shaft 13 so that these impellers are driven in unison at the crank-shaft speed. The compressor is provided with an in-take pipe 47 which is supplied with the motive fluid by means of the usual carburetor 48. Mounted on the crank-shaft 12 30 in balancing relation to the crank 26 and the parts connected therewith, are counterweights 49 which are suitably proportioned to provide a perfect dynamic balance. In a similar manner, the crank-shaft 13 is provided with the counterweights 50. Gears 51 are secured to the crank-shafts 12 and 13 and, being of the same diameter 35 and in mesh, cause the crank-shafts to rotate at all times at the same angular velocities.

In the operation of the engine above described, 40 assuming that the pistons 18 and 24 are moving to the right on the explosion stroke, the pistons 34 and 35 will be compressing a charge in the cylinders 30 and 31. When the pistons 18 and 24 uncover the ports 17 and 23, the burnt gases will 45 be exhausted through the ports 23 and a fresh charge will enter through the ports 17 and fill the cylinder 14 and pass through the transfer passage 39 into the cylinder 15 and, because of 50 their swirling motion, will effectively scavenge the burnt gases from both cylinders. At the end of the stroke of the pistons the charge in the cylinders 30 and 31 will be ignited by the spark plug 43 and the pistons will then move in the opposite direction, the ports 17 and 23 being thereby 55 closed by the pistons 18 and 24 and the charge being compressed in the cylinders 14 and 15. Toward the end of this stroke of the pistons, the inlet ports in the cylinder 30 and the exhaust ports in the cylinder 31 will be uncovered by the 60 pistons 34 and 35, thereby permitting the burnt gases to be exhausted from the cylinders 30 and 31 and a fresh charge supplied thereto. The pistons will then start on their stroke in the opposite direction and the operations will be repeated 65 so that two of the pistons will start on their power stroke every 180° of revolution of the crank-shafts.

In the engine illustrated in Figs. 6 to 9, the 70 crank case, cylinders, pistons, connecting rods and crank-shafts are substantially the same as

in the two-cycle engine above described, but this engine operates on the four-stroke cycle principle and, therefore, each of the cylinders is provided with an inlet valve 60 and an exhaust valve 61 and the head blocks 62 separate the interiors 5 of each pair of cylinders. The crank-shafts are also geared together for rotation in unison and at equal angular velocities at all times. The usual cam shafts 63 and 64 are provided and these cam shafts actuate push rods 65 which are operatively 10 connected with the rocker arms 66 which are suitably mounted on the head blocks 62 and operatively connected with the stems of the valves 60 and 61, according to common practice.

On the crank-shaft 67 there is a timing gear 15 68 which meshes with the gears 69 and 70 on the cam shafts 63 and 64, respectively, these timing gears being so proportioned that the cam shafts rotate at one-half the speed of the crank-shafts, according to the common practice in four stroke 20 cycle engines.

It is believed that the operation of the engine disclosed in Figs. 6 to 9 will be readily understood from the foregoing description and the drawings and, therefore, a detailed description 25 of the operation will be omitted. Since the unit comprises four cylinders, there will be an explosion stroke in one of the cylinders during each half revolution of the crank-shafts and, by providing each of the crank-shafts with suitably proportioned counterweights for the cranks and masses attached thereto, it will be apparent that the engine will operate in perfect dynamic balance.

Having thus described my invention, I claim: 35

1. An internal combustion engine comprising two parallel crank-shafts geared together for rotation in opposite directions at equal angular velocities, four cylinders with their axes in parallel relation, said cylinders being arranged in pairs on opposite sides of the common plane of the axes of said crank-shafts, pistons in said cylinders, connecting rods operatively connecting the pistons of two of said cylinders with a crank on one of said crank-shafts, connecting rods operatively connecting the pistons of the other two 45 cylinders with a crank on the other crank-shaft, the relation of said cranks being such that all of said pistons move, at all times, in unison and in the same direction, and means for controlling the motive fluid supply and exhaust for the different cylinders. 50

2. An internal combustion engine comprising two parallel crank-shafts geared together for rotation in opposite directions at equal angular 55 velocities, four cylinders with their axes in parallel relation and in a common plane, the axes of two of said cylinders being in a plane which includes the axis of one of said crankshafts, the axes of the other two cylinders being in a plane 60 which includes the axis of the other of said crank-shafts, pistons in said cylinders, connecting rods operatively connecting the pistons in the first mentioned two cylinders with a crank on one of said crank-shafts, connecting rods operatively connecting the pistons in the other two 65 cylinders with a crank on the other crank-shaft, the relation of said cranks being such that all of said pistons move, at all times, in unison and in the same direction, and means for controlling the 70 motive fluid supply and exhaust for the different cylinders.

3. An internal combustion engine comprising two parallel crank-shafts geared together for rotation in opposite directions at equal angular 75

velocities, four cylinders with their axes in parallel relation, said cylinders being arranged in pairs on opposite sides of the common plane of the axes of said crank-shafts, pistons in said 5 cylinders, connecting rods operatively connecting the pistons of two of said cylinders with the same crank on one of said crank-shafts, connecting rods operatively connecting the pistons of the other two cylinders with the same crank on the 10 other crank-shaft, counterweights on each of said crank-shafts for balancing said cranks and the masses attached thereto, the relation of said cranks being such that all of said pistons move, at all times, in unison and in the same direction, 15 and means for controlling the motive fluid supply and exhaust for the different cylinders.

4. An internal combustion engine comprising two parallel crank-shafts geared together for rotation in opposite directions at equal angular

velocities, four cylinders with their axes in parallel relation and in a common plane, the axes of two of said cylinders being in a plane which includes the axis of one of said crank-shafts, the axes of the other two cylinders being in a 5 plane which includes the axis of the other of said crank-shafts, pistons in said cylinders, connecting rods operatively connecting the pistons in the first mentioned two cylinders with the same crank on one of said crank-shafts, connecting 10 rods operatively connecting the pistons in the other two cylinders with the same crank on the other crank-shaft, counterweights on each of said crank-shafts for balancing said cranks and the masses attached thereto, and means for controlling 15 the motive fluid supply and exhaust for the different cylinders.
